J. D. NIXON

COMBINATION SET-DOWN AND SCREW-OFF PACKER

Filed Jan. 22, 1924

Jeddy D. Nixon Inventor

By Jesse R. Stone

Att. Attorney

UNITED STATES PATENT OFFICE.

JEDDY D. NIXON, OF HOUSTON, TEXAS, ASSIGNOR TO W. K. M. COMPANY, INC., OF HOUSTON, TEXAS.

COMBINATION SET-DOWN AND SCREW-OFF PACKER.

Application filed January 22, 1924. Serial No. 687,695.

To all whom it may concern:

Be it known that I, JEDDY D. NIXON, a citizen of the United States, residing at Houston, Harris County, Texas, have invented a certain new and useful Improvement in Combination Set-Down and Screw-Off Packers, of which the following is a specification.

My invention relates to an improved combination packer for wells and pertains more particularly to packers employed in the pumping of deep wells for oil or water.

It is an object of my invention to provide a packer which may, if desired, be arranged to operate as a set-down packer in which no unscrewing operation is necessary, and which may also be employed if desired as a screw-off packer where such a type of device is desirable.

It is also an object to provide a device of this sort which may be positively operated without difficulty, and which comprises a minimum number of parts, thus making it economical in construction and easy to operate.

Referring to the drawing herewith, wherein like numerals of reference are employed to designate like parts in both the views, Fig. 1 is a central longitudinal section through a packer constructed in accordance with my invention. Fig. 2 is a broken central longitudinal section through the device showing the parts in different positions than those shown in Fig. 1.

I contemplate that the packer shown in the drawing may be used to close off the space between the tubing and the casing in a well which is being pumped, and the construction is intended to close off the escape of gas or other fluid upwardly between the tubing and the casing during the pumping operation. It is understood however that this construction may be employed to start a well flowing through the tubing where no pumping operation is desired.

In the drawing, the upper section 1 of the packer comprises a length of pipe swedged inwardly at the upper end, and threaded at 2 for connection with the tubing.

The lower end is threaded internally at 3 for connection to a special coupling 4. This coupling is threaded externally at its upper end 5 for connection with the section 1, and below the threaded portion the thickness of the coupling is increased at 6 so that the

outer diameter is spaced slightly from the interior wall of the casing. The inner face of the coupling is extended inwardly and threaded at 7 for connection with the tube 8.

The tube 8 has its wall slightly thickened at its upper end 9, to provide a threaded portion 10 of a slightly greater outer diameter than the remaining portion of the tube. This threaded portion is adapted to engage within the coupling 4 in such manner that the said coupling may be screwed downwardly to release its connection with said tube and remain out of engagement with the tube below the threaded portion. The lower end of the tube 8 is threaded externally for engagement within a nipple 11, which is swedged inwardly at its lower end and threaded internally at 12 for connection with the tubing of the well. The nipple 11 is of greater thickness than the tube 8, and extends outwardly therefrom at its upper end to provide a shoulder 13 which forms a seat for the sleeve 14 of rubber or other compressible composition forming the expandable packer.

The packer 14 is preferably divided into two parts, the lower sleeve 14 and the upper ring or collar 15 between the said sleeve and the lower shoulder 16 of the coupling 4. The collar 15 is of the same material as the packer sleeve, but is easily removable when desired so that the coupling 4 may be screwed downwardly out of threaded connection with the tube 8.

In the operation of the packer, the device may be screwed into the tubing at any point along its length where it is desired to set the same. The tubing will then be introduced into the well until the lower end thereof contacts either with the bottom of the well, or until the central portion of the nipple 11 rests upon the upper end of the liner within the well. If the weight of the tubing is then rested upon the packer, the friction of the lower end against the bottom of the hole or with the upper end of the liner will prevent its rotation so that the coupling 4 may be screwed downwardly upon the tube 8 and thus compress the packing 14 and 15, expanding it outwardly against the wall of the casing in an obvious manner so as to close the space between the casing and the tube by forming the upper end 9 of the tube 8 of a larger diameter than the remaining tube, the coupling 6 need be

screwed down but a short distance before it will be released, and will then telescope down over said tube to compress the packing. The tube itself, with the packing thereon, will not be rotated. This is called a screw-off packer because the unscrewing of the coupling 4 from the tube 8 is necessary to compress the packing. Ordinarily, it will not be necessary to screw the coupling down out of threaded engagement with the upper end of the tube in order to sufficiently expand the packer, but if this does become necessary, the weight of the tube upon the coupling 4, after it has been disengaged from the tube, will be sufficient to entirely expand the packer.

This device may be used as a set-down packer by removing the upper ring or collar 15 of the packer, and by then screwing the coupling 4 downwardly to a position below the threaded portion 9, so that the tube and the packer will hang on the lower end of the coupling 4 approximately as shown in Fig. 2. The device may be then lowered into the well until the lower end of the tubing strikes the bottom of the well or the upper end of the liner and the lowering of the tubing thereafter will force the coupling 4 downwardly to expand the packing 20 against the casing 17, as illustrated in Fig. 2.

The combining of the set-down and the screw-off features makes this device an especially desirable one for use in connection with pumping operations and also in causing wells to flow which otherwise would not themselves produce oil through the casing alone. The set-down construction may be employed where it is not desirable to rotate the tubing, but the screw-off construction will be employed where conditions allow, and it will be noted that the tool is exceedingly simple and economical to construct.

Further objects and advantages of my invention will be apparent to those skilled in the art without further description.

What I claim as new, and desire to protect by Letters Patent is:

1. A well packer comprising a pipe member, a coupling thereon, a tube having an upper end of increased outer diameter threaded for connection in said coupling, a lower nipple on said tube, and a packing sleeve on said tube between said coupling and said nipple said coupling being adapted to be screwed downwardly out of threaded engagement with said tube to expand said packing.

2. A well packer comprising an upper tubular member, a coupling therein having

a thickened lower shoulder, a tube having an upper end of larger external diameter than the remainder of said tube, said upper end being threaded to engage within said coupling, a nipple on the lower end of said tube, and a packing sleeve of compressible material between said nipple and the shoulder of said coupling whereby the turning of said coupling in a right hand direction will force the downward movement of said coupling to compress said packing sleeve longitudinally.

3. A well packer comprising a tubular member adapted to be connected with the pump tubing, a coupling on the lower end of said member, an internally threaded lower end on said coupling of smaller internal diameter than the remainder of said coupling, a tube having an enlarged upper threaded end to fit within said coupling, a lateral shoulder on the lower end of said tube, a packing sleeve on said tube above said shoulder, and a packing ring above said sleeve, said coupling bearing against said ring.

4. A well packer for connection in a string of tubing, including a coupling having its lower end decreased in internal diameter and threaded, a tube having its cylindrical upper end enlarged in diameter and threaded to engage within said coupling, a packing sleeve on said tube, a supporting shoulder on said tubing for said sleeve, and a separate packing ring between said sleeve and said coupling for the purpose described.

5. A well packer for connection in a string of tubing for wells, including a coupling reduced in internal diameter at its lower end and threaded, a tube having its upper end enlarged and threaded to engage within said coupling, a supporting shoulder on the lower end of said tube and a packing sleeve on said tube between said shoulder and said coupling.

6. A well packer for connection in a string of pipe including a coupling member, a tube having a detachable connection within the lower end thereof, a supporting shoulder on the lower end of said tube, a packing sleeve of compressible material on said tube and seated on said shoulder, and means to disengage said coupling from said tube and compress said packing sleeve longitudinally.

In testimony whereof I hereunto affix my signature this 16th day of January, A. D. 1924.

JEDDY D. NIXON.
